UNITED STATES PATENT OFFICE.

GEORGE GRIFFIN HUGHES AND JOHN FLACK McDUFFIE, OF BESSEMER, ALABAMA.

MINING SYSTEM.

1,221,860.

Specification of Letters Patent. Patented Apr. 10, 1917.

Application filed January 8, 1912. Serial No. 669,294.

To all whom it may concern:

Be it known that we, GEORGE G. HUGHES and JOHN F. McDUFFIE, citizens of the United States, residing at Bessemer, in the 5 county of Jefferson and State of Alabama, have invented certain new and useful Improvements in Mining Systems, of which the following is a specification.

The object of the present invention is to 10 facilitate the removal of coal, ore, and other material from mines.

The question of labor is of great moment with mine operators and a machine which will decrease labor would be of the very 15 greatest value. At present the ore, coal, and other material, which is taken from mines, is loaded on tram cars by hand, necessarily taking a great deal of time, increasing the cost and greatly endangering life, 20 on account of the number of people so employed.

As is well known there are two systems of mining in use in the United States. These are known as the "long wall" system, and the "room and pillar" system. In 25 the "long wall" system, the mine is laid out in blocks of from 300 to 600 feet wide and the whole block is worked out at once, taking everything and leaving no support 30 for the top except the timber which is placed there for that purpose. This system is used in mining very thin veins of coal.

In the "room and pillar" system headers are driven substantially at right angles to 35 the slope leading to the surface, and rooms are worked substantially at right angles to these headers. The rooms are from 25 to 50 feet wide with a pillar of coal or ore between each two rooms to support the top.

40 It is in the "room and pillar" system that our machine is particularly designed to work. The manner in which our invention is carried out is given in the following description in connection with the appended drawings in which Figure 1 shows a diagram of the "room and pillar" system; Fig. 2 is a side elevation of a room and our machine; Fig. 3 is an elevation of our machine; and Fig. 4 is a modification of our machine.

45 In Fig. 1 a slope is shown on the right and a header leading therefrom. Several rooms are shown leading from this header. It is obvious that there may be as many headers and rooms as desired. Their number, as well as the number of slopes, is governed by the circumstances of each case.

As shown in Fig. 1 there are tracks laid

for tram cars in the slope and header. There is also a second track laid in the headers and extended into the rooms for the 60 purpose of carrying the machine from one room to another and also for carrying it into each room. There may be as many lines of tram track as desired with suitable cross-overs for switching from one to another. 65

In Fig. 2 is shown the machine in position to enter a room. It will be noted that the room is inclined at 30°, but it is obvious that it might be at any angle, or level. The track supported on column S runs longitudinally of the header and passes in front of the rooms. This track may be placed on the ground as in Fig. 4. On this track run the wheels E which carry sections of track B. These sections carry a bridge Z 75 and mounted on this bridge is a trolley consisting of motors, cable, drum and bucket, etc. The detailed arrangement of the motors for propelling the wheels E, the bridge Z and the trolley are not shown, but they 80 are shown only diagrammatically since these details form no part of our invention, but we do claim to be the first to use independent means for obtaining three independent directions of movement for an excavating 85 means such as the bucket A as described hereinafter. The sections of track remain on the track S, while the bridge is arranged to go into each room on a track H laid therein. The bridge is propelled into the 90 rooms by means of a suitable motor in conjunction with the rack K and pinion P', or any other suitable means. The short sections of track B may be alined with the track H in the rooms thereby permitting 95 the bridge to pass into the rooms. The machine is so constructed that it will pass clear of the pillars.

The trolley carries the bucket or shovel A for scooping up the coal, ore, or other material, and this bucket is hinged at one end to the member C on the bridge Z and the other end is operated up and down by the tackle and cable R which passes around a suitably driven drum. It will be noted that 100 the bucket is so arranged that it can be loaded and unloaded with a very small head. That is to say, it is suspended underneath the trolley and so hung that it can be forced forward to load and can then be unloaded 105 without being hoisted higher than the trolley track. This is of very great advantage for the reason that the hanging wall of these rooms is usually comparatively low.

The means for carrying the material from the bucket to the cars is shown as a trough O, but any equivalent means may be used with equal results.

5 As seen in Fig. 3 the trolley may move from one side of the room to another on the beams G G of the bridge Z, so that material may be gathered from any point in the rooms.

10 In Fig. 4 is shown a modification of our machine, the only change being that of placing the wheels E at the bottom of columns S' so that they are driven on tracks A' which are placed on the ground along-
15 side the tram tracks. The advantage of this is obvious, it being much cheaper to place the track on the tram ties than to construct an elevated track. The tram track is placed between the rails on which the ma-
20 chine runs. In this arrangement the ma-
chine is propelled by a suitable motor con-
nected through any suitable gearing. The
details are not shown as they are not a part
of our invention and would only complicate
25 the drawings.

The operation of the system is as follows:

The machine is run along the tracks S on the wheels E by a suitable motor until it is brought into proper position in front of a
30 room. The bridge Z carrying the trolley then goes into the room on the tracks H and carries with it the bucket A. The front end of the bucket is lowered so as to come into contact with the material to be removed and
35 is then forced forward by means of a suitable motor until the bucket is loaded. The front end is then elevated and the bridge runs back to the proper place and empties the contents of the bucket into the trough O
40 which empties into the tram car N. Then the machine may load other cars from this room, or it may come back onto the sections of track B and the whole machine be moved over to the next room and a similar opera-
45 tion performed. When the tram is loaded it is carried to the surface in the usual way.

From the above it is seen that three independent directions are obtained as many means, that is, the longitudinal direction along the header, the direction into the room of the bridge Z, leaving the track behind, and the direction of the trolley in the room which is independent of the bridge.

It will be understood, of course, that many
55 modifications of the above described arrangement will suggest themselves to those skilled in the art, but it must be understood that we do not confine our invention to the specific construction and arrangement here-
60 in shown, except in so far as it is limited by the scope of the claims annexed hereto.

Having described our invention, what we claim is:—

1. In a system of the character described, a slope, headers and rooms, tracks in same, a 65 second track adjacent a plurality of said rooms and on a level with the entering end of said room tracks, means mounted on said second track capable of passing from one room to another and entering each room for 70 taking material therefrom and means mounted on said first named track, for receiving and conveying said material to the surface.

2. In a system of the character described, 75 a slope, headers and rooms, tracks in same, a second track in said headers, and on a level with the entering end of said room track, means mounted on said second track capable 80 of being moved longitudinally of said headers, longitudinally of said rooms and transversely of said rooms for removing material from any portion of any of said rooms and means for receiving and conveying said material to the surface.

3. In a system of the character described the combination of a slope, headers and rooms, a track therein, a second track in said headers, the entering end of the room tracks being on a level with said second track, 90 power-propelled means mounted on said second track adapted to be moved longitudinally of said headers, sections of track carried by said first means and adapted to be aligned with the room tracks, a bridge mounted on said sections of track and adapted to be moved off said tracks and onto the room tracks and longitudinally of said rooms, a trolley carried by said bridge and mounted on a track also carried by said bridge, said trolley being adapted to be moved on the bridge tracks transversely of said rooms and a bucket carried by said trolley and adapted to remove material from any point of any of said rooms.

4. In a system of the character described, a slope, headers and rooms, a track in same, a second track in said headers, the entering end of the room tracks being on a level with said second track with the main portion of 110 said room track at an incline to said second track and means capable of entering on said room track and removing material from said rooms.

In testimony whereof we affix our sig- 115 natures in presence of two witnesses.

GEORGE GRIFFIN HUGHES.
JOHN FLACK McDUFFIE.
